UNITED STATES PATENT OFFICE.

CHARLES F. HUNTOON, OF CHICAGO, ILLINOIS, ASSIGNOR TO CHICAGO RAILWAY EQUIPMENT COMPANY, OF CHICAGO, ILLINOIS, A CORPORATION OF ILLINOIS.

REVERSIBLE GUARD-FINGER CLAMP FOR BRAKE-BEAMS.

SPECIFICATION forming part of Letters Patent No. 699,842, dated May 13, 1902.

Application filed February 18, 1902. Serial No. 94,628. (No model.)

To all whom it may concern:

Be it known that I, CHARLES F. HUNTOON, a citizen of the United States, residing at the city of Chicago, county of Cook, State of Illinois, have invented a certain new and useful Improvement in Reversible Guard - Finger Clamps for Brake-Beams, of which the following is a full, clear, and exact description, such as will enable others skilled in the art to which it appertains to make and use the same, reference being had to the accompanying drawings, forming part of this specification, in which—

Figure 1 is a plan view of my improved guard-finger clamp, showing the same in position on one end of a brake-beam. Fig. 2 is a sectional view on line 2 2, Fig. 1. Fig. 3 is a horizontal sectional view, and Fig. 4 is an end elevational view as seen from the inside.

This invention relates to a new and useful improvement in guard-finger clamps for brake-beams, the object being to construct the device in such manner that a plurality of sockets are provided for the guard-finger, which sockets are so constructed that the medium which secures the clamp in position on the brake-beam will also clamp the guard-finger in either of said sockets.

With these objects in view my invention consists in the construction, arrangement, and combination of the several parts, all as will hereinafter be described and afterward pointed out in the claims.

In the drawings, 1 indicates the compression member of a brake-beam, in this instance being shown as a solid rectangular bar, although it is obvious that said compression member may be any shape in cross-section, the jaws of the guard-finger clamp which embrace the same being shaped correspondingly.

2 indicates the tension member of the brake-beam, in this instance shown as a circular rod, which rod is embraced by my improved guard-finger clamp. However, I will state that neither the shape nor arrangement of the compression or tension members of the brake-beam has anything to do with my improved guard - finger clamp, which with obvious changes can be adapted to all existing forms of brake-beams with which I am familiar.

The guard-finger clamp shown is made up, essentially, of two jaws 4 and 5, whose free ends are formed with seats 6 to embrace the brake-beam or a member thereof—in this instance the compression member. The opposite ends of the jaws are connected by a curved end 7, which is obliquely disposed to accommodate the tension member of the type of beam shown in the drawings.

8 indicates overhanging hoods extending outwardly from the inner edges of the jaws 4 and 5, the free ends of said hoods or recurved portions being provided with perforated ears 9, which align with hollow bosses 10 on the jaws 4 and 5. These overhanging hoods form sockets or seats for the guard-finger, (indicated by dotted lines 11,) and when the clamp is in position the guard-finger is inserted in its socket, one end thereof preferably abutting against the shoulder or projection on the free end of the jaw, which results from the formation of the seat in said free end. A bolt 12 is now passed through the lugs and bosses 9 and 10 on each jaw, and upon screwing the nut tightly home it will be obvious that not only will the overhanging hood clamp the guard-finger in position, but the jaws 4 and 5 will be forced tightly against the member of the brake-beam arranged in the seats between their free ends. In this operation the curved end wall 7 serves as a fulcrum, while the securing-bolt acts to apply the power, and the member of the beam between the free ends of the jaws offers the resistance. Thus both jaws are substantially modified forms of levers of the second order.

While I have shown the clamp as being made from a casting, it is obvious that the same could readily be stamped and formed from sheet metal; also, that instead of the overhanging hoods extending from the edges of the jaws said hoods could extend from other points of the jaws. In any event the prime object is to insure the clamping and holding of the guard-finger in position in its socket on the guard-clamp and the clamping and holding of said guard-clamp in position on the brake-beam by a single securing medium, and this is effected, as will be readily seen, by so constructing the guard - finger

clamp that the ends of the clamping-jaws which engage the brake-beam are free to move and that one end of the overhanging hood is likewise free to move and in a direction corresponding to the direction of movement of the free ends of the jaws, whereby upon the application of power to the free end of the overhanging hood the jaw to which it is attached is likewise affected by said power and moved in the same direction. The securing-bolt applying equal power to the free end of the overhanging hood on the opposite jaw will affect said hood and move said jaw in an opposite direction to effect the clamping action referred to.

From the above it will be observed that the clamp is capable of being applied in position at either end of the beam and to that extent may be said to be universal, in that the same pattern answers for both right and left.

I am aware that many minor changes in the construction, arrangement, and combination of the several parts of my device can be made and substituted for those herein shown and described without in the least departing from the nature and principle of my invention.

Having thus described my invention, what I claim as new, and desire to secure by Letters Patent, is—

1. A guard-finger clamp for brake-beams formed with a plurality of sockets for the reception of the guard-finger and a seat for a member of the brake-beam, and means for clamping the guard-finger in either of said seats and coincidentally securing the device in position on a brake-beam member; substantially as described.

2. A guard-finger clamp for brake-beams consisting of jaws connected at one end, and being provided with an overhang having one free end, said overhang being designed to embrace the guard-finger; substantially as described.

3. A guard-finger clamp for brake-beams consisting of two jaws connected at one end, and a curved extension free at one end and provided with an opening in its free end for the passage of a securing-bolt, said curved extension being designed to embrace the guard-finger; substantially as described.

4. A guard-finger clamp for brake-beams

consisting of two jaws connected at one end, and two curved extensions provided with openings in their free ends, whereby a guard-finger may be secured in position in either of said curved extensions and the device coincidentally clamped in position on a brake-beam member; substantially as described.

5. A guard-finger clamp comprising two jaws connected at one end and having seats 60 for embracing a brake-beam member between their free ends, and overhanging hoods extending from the edges of said jaws and provided with alining openings in their free ends, either opening being capable of receiving a 65 guard-finger; substantially as described.

6. A guard-finger clamp for brake-beams consisting of two jaws connected at one end and formed with seats at their opposite or free ends, overhanging hoods extending from 70 the edges of said jaws and being provided with perforated lugs on their free ends, and hollow bosses formed on said jaws in alinement with the perforated lugs on said overhanging hoods; substantially as described.

7. A guard-finger clamp having a plurality of sockets whereby said clamp may be secured in position at either end of the beam, and a reversible guard-finger clamp; substantially as described.

8. A guard-finger clamp having jaws for attachment to the beam and a plurality of clamp folds or ears, either of which is adapted to hold a guard pin or finger; substantially as described.

9. A guard-finger clamp consisting essentially of two members having parallel folds for separately coöperating with the guard pin or finger; substantially as described.

10. A guard-finger clamp consisting essentially of two members each of which is provided with a fold or ear, said folds or ears being in vertical alinement and designed to separately coöperate with a guard pin or finger; substantially as described.

In testimony whereof I hereunto affix my signature, in the presence of two witnesses, this 11th day of February, 1902.

CHARLES F. HUNTOON.
